COMB

Cella Poetto, New York, N. Y., assignor to Bruce
King, New York, N. Y.

Application November 28, 1952, Serial No. 323,047

2 Claims. (Cl. 132—156)

1

This invention relates to a new type of toilet and/or pocket comb, which can be produced from any suitable plastic, rubber or other known material, and which has a portion carrying the teeth which is, by virtue of its construction and design, elastically or flexibly adaptable to the contour of the head.

The primary object of this invention is to provide for a toilet or pocket comb made of a single piece of material, which is designed in such manner, that one portion of the comb is rigid and serves as a solid holder or body, while the other portion, carrying the teeth, is elastic or flexible to the contour of the head when in use.

A further object of the present invention is to provide an economical, efficient and simply constructed comb, having a flexibly toothed body portion adapted to give under relatively light pressure.

The advantage of this new type of comb resides in its elastic adaptability to the contour of the head within itself without having other parts, serving for instance as a holder, attached or fixed to the flexible portion of the comb which could get loose or lost when in use, thus making the comb useless.

Further objects and advantages of the invention will appear from the following disclosure thereof together with the attached drawing which illustrates a preferred form of embodiment thereof, and in which:

Figure 1 is a front view demonstrating a possible construction of the invention showing the portion carrying the teeth undeflected;

Figure 2 illustrates how the portion carrying the teeth may be elastically deflected;

Figure 3 is a cross section on the line 3—3 in the center of the comb; and

Figure 4 is a cross section on the line 4—4 near the end of the comb.

The invention described hereinafter and illustrated by the accompanying drawing is obviously not limited to this description and design which may serve merely as an example and as one possible form of the invention.

In Figures 1 to 4 of the drawing is illustrated how the comb is formed with a body 11 having a reinforced upper portion or holder 12. The teeth 13 of the comb are cut or formed or pressed on the lower portion 14 of the body 11. A longitudinal slot 15 is cut, milled, formed or pressed in the body 11 between the reinforced upper portion

2

12 and the lower portion 14 of the body 11 carrying the teeth 13. A further recess 16 in the center of the reinforced upper portion 12 is provided to allow the lower portion 14 of the body 11 carrying the teeth 13 to deflect elastically upwardly. The slot 14 ends on both sides of the reinforced upper portion 12 in enlarged substantially round holes 17 which serve to stress-relieve the remaining body part connection between the upper and the lower portions when the latter carrying the teeth is deflected, and thus prevent the comb from breaking, adding at the same time a greater flexibility to the lower portion.

This description and illustration does not limit my present invention to the described design, but may as well pertain to all other varieties within the scope of the attached claims.

The body 11 of the comb may be made of any suitable material which will adapt the comb for the intended purpose, such as plastic, rubber or synthetic rubber.

What I claim is:

1. A comb comprising a one-piece body having a reinforced non-deflecting upper portion and teeth projecting from its lower portion and having a longitudinal slot between the upper and the lower portions, a recess centrally located in the reinforced upper portion to provide for an enlarged elastic adaptability of said lower portion carrying said teeth to the contour of the head.

2. A comb comprising a one-piece body having a reinforced non-deflecting upper portion and teeth projecting from its lower portion and having a longitudinal slot between the upper and the lower portions and a recess in the reinforced upper portion, both slot and recess providing for an enlarged elastic adaptability of said lower portion carrying said teeth to the contour of the head, said slot ending on both ends of the reinforced non-deflecting upper portion in an enlarged opening for stress-relieving and greater flexibility of the lower portion carrying the teeth when elastically deflected.
